(57) **CLAIM**

The ornamental design for a packaging for fraud detection in a portable device, as shown and described.

DESCRIPTION

FIG. 1 is a front perspective view showing our new design for a packaging for fraud detection in a portable device, having a hinge about which a portable device can be pivoted, the view showing the portable device having been pivoted about the hinge so as to be substantially outside of the packaging, where the portable device is shown in broken line and is not part of the design sought to be patented;

FIG. 2 is a left side elevational view of the packaging seen in FIG. 1;

FIG. 3 is a front elevational view of the packaging seen in FIG. 1;

FIG. 4 is a right side elevational view of the packaging seen in FIG. 1;

FIG. 5 is a rear elevational view of the packaging seen in FIG. 1;

FIG. 6 is a top plan view of the packaging seen in FIG. 1; and, FIG. 7 is a bottom plan view of the packaging seen in FIG. 1. The broken (dashed) lines showing the portable device contained within the package in FIGS. 1-7 are for illustrative purposes only; and form no part of the claimed design.
